LATCHING MEANS FOR WINDOW
MEETING RAILS

Harry A. Kaufmann, Detroit, Mich., assignor to
The Kaufmann Corporation, Detroit, Mich., a
corporation of Michigan

Application November 6, 1950, Serial No. 194,340

4 Claims. (Cl. 20—55)

1

This invention relates in general to a sealing device for the meeting rails of a double hung storm or auxiliary window and particularly to a type thereof for preventing separation of the said meeting rails in a said storm window having metal sash.

Metal sash for storm windows have been found particularly desirable because of their strength, light weight, pleasant appearance and minimum obstruction to light. The use of rolled or extruded, metal structural forms provides a highly satisfactory sash accomplishing these purposes. Examples of this type of sash construction may be found in my Patents Nos. 2,292,273 and 2,359,756. However, because of the resulting small cross-section of the rails of the sash, said rails often are excessively flexible, especially where large windows are involved.

Accordingly, a strong wind, for example, will tend to separate the meeting rails of a double hung storm window having metal sash, thereby creating air leakages and sometimes objectionable rattling. Attempts to overcome this problem have been made by providing meeting rail latches or locks of one type or another. However, in general, present latches are large, complicated, clumsy structures, unsuitable for use with the small metal rails usually utilized for storm windows. Such latches require greater mounting space than is provided along the rails of metal sash, and their size makes them objectionable in appearance. Even the more suitable latches are not adapted to use in installations where the space is small between the main window sashes and the storm window sashes.

Accordingly, it is a principal object of my invention to provide a sealing device for the meeting rails of a double hung storm window having metal sash, which will hold the meeting rails tightly together.

A further object of my invention is to provide a sealing device for a meeting rail, as aforesaid, adapted to use in installations having a small spacing between the permanent sashes and the storm or auxiliary sashes.

A further object of my invention is to provide a sealing device for meeting rails, as aforesaid, having simple structure and operation.

A further object of my invention is to provide a sealing device for meeting rails, as aforesaid, which is readily adjustable for compensating irregularities in the construction of either the permanent window or the auxiliary window.

Other objects and purposes of my invention will be seen by those acquainted with the design and

2

construction of windows, screens and similar articles upon reading the following specification and referring to the accompanying drawings in which:

5 Figure 1 is an oblique view of my improved sealing device for meeting rails mounted in its normal position of use.

Figure 2 is a horizontal, sectional view of a window equipped with my improved sealing device taken immediately above the meeting rails.

Figure 3 is a top plan view of said sealing device.

In the following description the terms "upwardly" and "downwardly" when used, will have reference to the sealing device and/or windows when disposed in their normal position of use. The terms "inwardly" and "outwardly" or their derivatives will have reference to the inside and outside of the windows with respect to the building with which said windows are used.

Referring to Figures 1 and 2, the numeral 1 indicates the upper rail of a conventional, main lower window sash and the numeral 2 indicates the lower rail of a conventional, main upper window sash. The upper rail 1 and the lower rail 2 are designed to seat together, as shown in Figure 1, and collectively to constitute the meeting rails 3 of the permanent or main window 4. The said main sashes, hence the meeting rails 3, are held against inward and outward movement by conventional means, such as guide strips 17 and the blind stops 18.

The auxiliary or storm window 5 consists of an upper sash having a lower rail 6 and a lower sash having an upper rail 7. The rails 6 and 7 are designed to lie side by side, when the storm window 5 is closed, and collectively constitute the meeting rails 8 of the storm window. The meeting rails 8 of the storm window 5 are normally parallel with, and spaced apart, in substantially the same horizontal plane from the meeting rails 3 of the main window 4, but, insofar as this invention is concerned, these parts may vary vertically or horizontally with respect to each other freely within the limits permitted by the usual requirements of storm window construction.

The sashes of the storm window are held against inward movement by the blind stops 18 and against outward movement by any conventional means, not shown. It will be understood that any suitable installation arrangement for the windows is contemplated in my invention. The storm window 5 is provided with glass panels 9, and the permanent window 4 is provided with glass panels 10. It will be understood, however, that although glass panels

40

45

50

55

are shown, other panels, such as insect or sun screening, may be used.

The sealing device 11 (Figures 1 and 3) is comprised of a flat, substantially rectangular body 20 having a pair of co-planar, upwardly extending pressure flanges 12 and 12a which are integral with the outward edge of the body 20, spaced from each other and perpendicular to the plane of said body. A pair of parallel, downwardly extending gripping flanges 13 and 13a, which are each integral with the respective side edges of the body 20, are disposed adjacent to the inward edge of the body 20 and spaced from the outward edge thereof. Notches 21 and 21a in said side edges of said body 20, between the forward edge and said gripping flanges, permit the easy formation of said gripping flanges from a single metal plate.

A slot 14 (Figure 3), which is provided in the body 20 and extends substantially diagonally across said body, is comprised of a positioning portion 22 and a locking portion 23. The positioning portion 22 is preferably disposed at an angle of between 45° and 90° to the plane of the pressure flanges, whereas the locking portion 23 is disposed at an angle of between about 10° and about 30° to said plane. The distance between the outward end of the positioning portion 22 and the outward end of the locking portion 23 measured along a line perpendicular to said plane is preferably substantially equal to the minimum spacing normally found between the storm window meeting rails 3 and the main window meeting rails 2.

The sealing device 11 is slidably mounted to the downward face of the lower rail 2 of the permanent window 4 by conventional means, such as a screw 15, which passes through the slot 14, and a washer 16 between the screwhead and the body 20. The gripping flanges 13 and 13a extend downwardly when the sealing device 11 is thus mounted. The pressure flanges 12 and 12a extend upwardly from the plate 20 and at least a part of each thereof is positioned in substantially the same horizontal plane as at least a part of the storm meeting rail 3, sufficient registry being provided that upon horizontal outward movement of the pressure flanges 12 and 12a they will firmly engage the storm meeting rail 3. The vertical extent of the pressure flanges 12 and 12a, conveniently about five-eights inch in a typical construction, is sufficient to permit all of the vertical variation of the storm window meeting rails with respect to the main meeting rail 2 which is ordinarily permitted anyway by the usual requirement in designing storm windows that the meeting rails thereof be substantially in a horizontal line with the main window meeting rails.

Having mounted a sealing device 11, as stated above, sealing of the rails 3 and 7 of the storm window 5 may be accomplished by first urging the device 11 outwardly until the pressure flanges 12 and 12a thereof bear against the adjacent side of the upper rail 7 of the lower storm sash. When such contact is made, the shank of the screw 15 will lie within the locking portion 23 of the slot 14. Accordingly, movement of the device 11 substantially sidewardly in the leftward direction, as appearing in Figures 2 and 3, will effect a wedging action between the rail 7 and the screw 15 by that part of device 11 lying between the plane of the flanges 12 and 12a and the outward wall of the locking portion 23 of the slot 14.

Since the meeting rails 3 of the main window 4 are relatively inflexible by comparison with the

meeting rails 8 of the storm window 5, this wedging action will cause the rail 7 to bow outwardly and snugly engage the rail 6. Friction will normally prevent dislocation of the sealing device 11 when thus wedged between the screw 15 and the rail 7. However, where opening of the storm window 5 is not contemplated for a long period of time, or where sill cleanout means are provided as shown in my Patent No. 2,435,008, dislocation of the device 11 may be positively prevented by tightening the screw 15.

Preferably, the device 11 is mounted at the center of the window, in which case only one is needed to effect a tight seal between the meeting rails 6 and 7 of the storm window 5, and one of said devices is entirely sufficient for the usual domestic size of window. Further, although more than one said sealing device may be used, if desired, a single, centered sealing device has been found preferable from the standpoint of providing a more effective seal.

When the sealing device 11 is fully retracted from the rails 8, it extends beyond the outward face of the rails 3 only by a distance equal to the thickness of the metal in the pressure flanges 12 and 12a, thereby constituting an obstruction to the movement of the sashes in either the permanent window or storm window which will be negligible for any ordinary spacing between the storm window and the permanent window. Further, unlike any of the conventional mechanical linkages devised for the same purposes as my invention, the outward pressure of the sealing device 11 against the meeting rail 3, being manually produced, can be accurately controlled. Accordingly, adjustment and compensation for irregularities in spacing between the window rails is a simple matter.

Modifications of my invention may be made without departing from the principle of my invention. Each of these modifications is to be considered as included in the hereinafter appended claims unless the language of these claims expressly states otherwise.

I claim:

1. In a sealing device for the meeting rails of a double hung storm window mounted adjacent to a double hung permanent window and upon the frame thereof, the meeting rails of said permanent window being parallel with and spaced horizontally from the meeting rails of the storm window, the combination comprising: a rectangular, flat body having inward and outward edges, the width of said body between said edges being substantially greater than the horizontal spacing between the respective meeting rails of said storm and permanent windows and a slot formed in said body diagonally arranged with respect to said edges, said slot having a locking portion at the inward portion thereof comprising over half of its length and disposed at a low angle to said outward edge, and having a positioning portion at the outward portion of said slot comprising less than half of its length and disposed at an angle to said outward edge greater than said low angle; means extending through said slot releasably and slidably securing said body to the lower surface of that meeting rail of said permanent window adjacent to said storm window, said means being spaced from the adjacent meeting rail of the storm window a distance which is intermediate the distances which the ends of the slot are spaced from said storm window meeting rail whereby said body may be urged outwardly into engagement with and retracted from said ad-

5 jacent storm window meeting rail by movement of said body with respect to said means, a pair of co-planar, spaced pressure flanges secured to and extending upwardly from the outward edge of said body for engagement with the adjacent meeting rail of said storm window when said body is urged outwardly thereagainst; and gripping means integral with said body, whereby said device may be manually engaged for urging same against the adjacent meeting rail of said storm window.

2. In a window assembly for a building structure having a substantially rigid double hung main window sash construction having a centrally disposed member held against inward and outward movement with respect to said building structure and a pair of relatively flexible double hung storm sashes each equipped with a meeting rail and spaced outwardly from said main window sash construction and held at their side edges against inward and outward movement with respect to said main window sash construction, means for holding the meeting rails for said storm sashes against inward and outward movement with respect to each other comprising: a member including head and shank portions extending downwardly from the lower surface of the bottom rail of the upper one of said double hung sash; a rectangular flat body having inward and outward edges, of width between said edges sufficient to extend from the inner surface of the inner one of said double hung storm sash to a point beyond the position occupied by said member and a slot formed in said body and diagonally arranged with respect to said edges, said slot having said member extending therethrough and being of a uniform width sufficient to permit a sliding clearance with respect to the shank of said member but permitting the head of said member to overlap both edges of said slot, and said slot further having an elongated locking portion including the inward end thereof and comprising over half the length of said slot and disposed at a low angle to said outward edge, and said slot also having a positioning portion including the outward end of said slot and comprising less than one half the length of said slot and disposed at an angle to said outward edge greater than said low angle; a pressure flange integral with the outward edge of said body and extending perpendicularly therefrom for engagement with said inner surface and gripping flanges integral with said body and extending downwardly substantially perpendicular with respect thereto.

3. In a window assembly for a building structure having a substantially rigid double hung main window sash construction having a centrally disposed member held against inward and outward movement with respect to said building structure and a pair of relatively flexible double hung storm sashes each equipped with a meeting rail and spaced outwardly from said main window sash construction and held at their side edges against inward and outward movement with respect to said main window sash construction, means for holding the meeting rails for said storm sashes against inward and outward movement with respect to each other comprising: a

5 member including head and shank portions extending downwardly from the lower surface of the bottom rail of the upper one of said double hung sash; a rectangular flat body having inward and outward edges, of width between said edges sufficient to extend from the inner surface of the upper rail of the lower one of said double hung storm sash to a point beyond the position occupied by said member and a slot formed in said body and diagonally arranged with respect to said edges, said slot having said member extending therethrough and being of a uniform width sufficient to permit a sliding clearance with respect to the shank of said member but permitting the head of said member to overlap both edges of said slot, and said slot further having an elongated locking portion including the inward end thereof and comprising over half the length of said slot and disposed at an angle to said outward edge greater than said low angle; a pressure flange integral with the outward edge of said body and extending perpendicularly therefrom for engagement with said inner surface and gripping flanges integral with said body and extending downwardly substantially perpendicular with respect thereto.
